Primary Examiner — Ricky Pham(57) **CLAIM**

The ornamental design for the electric heating plates, as shown and described.

DESCRIPTION

FIG. 1 is a top and front perspective view of an electric heating plates design showing my new design.

FIG. 2 is a bottom and rear perspective view of the electric heating plates.

FIG. 3 is a front view of the electric heating plates.

FIG. 4 is a rear view of the electric heating plates.

FIG. 5 is a left side view of the electric heating plates.

FIG. 6 is a right side view of the electric heating plates.

FIG. 7 is a top view of the electric heating plates.

FIG. 8 is a bottom view of the electric heating plates.

FIG. 9 is an enlarged view of callout “FIG. 9” shown in FIG. 1.

FIG. 10 is an enlarged view of callout “FIG. 10” shown FIG. 1; and,

FIG. 11 is an enlarged view of callout “FIG. 11” shown FIG. 2.

Any shading and cross-hatching are not features of the design but are utilized to illustrate the surface contours of the electric heating plates design in the drawings.

1 Claim, 11 Drawing SheetsFIG.11
